UNITED STATES PATENT OFFICE.

SAMUEL M. VAUCLAIN, OF PHILADELPHIA, PENNSYLVANIA.

VALVE FOR COMPOUND ENGINES.

SPECIFICATION forming part of Letters Patent No. 660,474, dated October 28, 1900.

Application filed May 24, 1900. Serial No. 17,882. (No model.)

To all whom it may concern:

Be it known that I, SAMUEL M. VAUCLAIN, a citizen of the United States, residing in Philadelphia, Pennsylvania, have invented 5 certain Improvements in Valves for Compound Engines, of which the following is a specification.

The object of my invention is to provide a compound engine with a single valve common 10 to both the high and low pressure cylinders which is so designed that the steam will enter at the center and exhaust at the ends, thus making a balanced valve and a cylinder-casting having comparatively short and straight 15 passages.

In the accompanying drawings, Figure 1 is a longitudinal sectional view of my improved valve with sufficient of the valve-chest to illustrate my invention. Fig. 2 is a sectional 20 view through the cylinder and valve-chest on the line 2 2, Fig. 1: Fig. 3 is a sectional view on the line 3 3, Fig. 1; and Fig. 4 is a sectional view on the line 4 4, Fig. 1.

A is a casting containing the high and low 25 pressure cylinders B and D and the valve-chest C. The casting shown forms part of a locomotive-engine, Fig. 2 showing one-half of the saddle.

a is the steam-inlet passage to the valve-chest, and b is the exhaust-passage.

The valve-chest C has a bushing c, and this bushing is perforated at the ports to permit the steam to enter and exhaust from the valve-chest.

35 It will be understood that other forms of cylinder structures may be used without departing from my invention.

Referring to Fig. 1, S is the steam-inlet port, communicating with an inlet-passage a in 40 the cylinder-casting, and on each side of this steam-inlet port are the ports H H, leading from the valve-chest to the high-pressure cylinder B. At each end of the chest are the exhaust-ports E E, forming communication 45 between the chest C and the exhaust-passage b, while between the exhaust-ports E and the high-pressure ports H are the ports L, leading from the valve-chest to the low-pressure cylinder B. It will be seen that the steam- 50 inlet port is at the center and the exhaust-ports are at each end and the ports leading

to the two cylinders between the exhaust-ports and the central steam-port.

F is a hollow piston-valve formed in the manner shown in Fig. 1, having an annular 55 passage f at the center, which is of a sufficient size that when it is shifted it will allow steam to pass to either of the high-pressure ports. The piston is hollow, as mentioned, and at each end are ports f', which communicate with each other through the body of the piston, and these ports f' are so proportioned that they will form a communication between the ports leading from the high pressure on the one side to the low pressure on the opposite side. Each end of the valve is closed, and the valve is so proportioned that it will uncover one or other of the low-pressure ports 60 to exhaust as it is reciprocated.

F' is the valve-rod, which passes through an 70 ordinary stuffing-box c' in the head C' of the chest.

When the valve is in the position shown in Fig. 1, the steam is cut off from the high-pressure cylinder, and the low-pressure cylinder 75 is also cut off from the high-pressure cylinder, and one of the low-pressure cylinders is slightly uncovered to exhaust.

When the valve is moved in the direction of the arrow, Fig. 1, the port L at the forward end of the chest will be uncovered and will communicate with the opposite end of the high-pressure cylinder through the port H at the rear, and the port at the forward end will communicate with the live-steam 85 port S through the annular passage f in the piston, and the low-pressure port L at the rear will communicate with the exhaust. When the valve F is returned, the direction of steam will be reversed. Thus I am enabled 90 to control the flow of steam from the steam-inlet port of the high-pressure cylinder and from the high-pressure to the low-pressure cylinder and from the low-pressure cylinder to exhaust with a single valve in 95 which the steam-inlet port is at the center and the exhaust-ports at each end.

My invention is an improvement upon the Letters Patent granted to me on the 25th day of June, 1889, No. 406,112.

I claim as my invention—

1. The combination in a valve structure for

compound engines, of a valve-chest having a port connected to the source of steam-supply at the center, ports connected to the exhaust at each end, and having intermediate ports leading to the high and low pressure cylinders, with a hollow valve having a central annular channel *f* and ports at each side of the channel communicating with each other through the valve, substantially as described.

10 2. The combination in a valve for compound engines, of the high and low pressure cylinders situated side by side, a valve-chest common to both cylinders, a steam-chest having a central supply - port communicating with the supply-passage in the cylinder-casting and exhaust-ports at each end communicating with the exhaust-passage of the cylinder-casting, and one set of high-pressure ports at

each side of the central steam-inlet port communicating with the ends of the high-pressure cylinder, and low - pressure ports communicating with each end of the low-pressure cylinders, said low - pressure ports opening into the chest between the high - pressure ports and the exhaust-ports, with a hollow valve having a central annular steam-passage and ports at each end communicating with each other, substantially as described.

In testimony whereof I have signed my name to this specification in the presence of 30 two subscribing witnesses.

SAMUEL M. VAUCLAIN.
